(57) **CLAIM**

The ornamental design for a tool holder assembly, as shown and described.

DESCRIPTION

FIG. 1 is a perspective view of an assembly of the tool holder assembly showing my new design.

FIG. 2 is a front elevational view of FIG. 1 showing my new design.

FIG. 3 is a rear elevational view of FIG. 1 showing my new design.

FIG. 4 is a left side elevational view of the tool holder assembly showing my new design.

FIG. 5 is a right side elevational view of the tool holder assembly showing my new design.

FIG. 6 is a top plan view of the tool holder assembly showing my new design.

FIG. 7 is a bottom plan view of the tool holder assembly showing my new design.

FIG. 8 is a perspective view of the tool holder assembly showing my design, the figure being shown with screwdrivers in phantom lines, the screwdrivers being shown for illustrative purposes only and forming no part of the claimed design; and,

FIG. 9 is a perspective view of the tool holder assembly similar to FIG. 8, showing the support arms in alternate positions, the figure being shown with screwdrivers in phantom lines, the screwdrivers being shown for illustrative purposes only and forming no part of the claimed design.
